APPARATUS FOR HEAT-TREATING
AIR-PERVIOUS STRIP MATERIALHarold J. Walter, Uxbridge, Mass., and
Paul R. Rose, East Orange, N. J.

Application November 16, 1945, Serial No. 629,087

1 Claim. (Cl. 34—160)

1

This invention relates to apparatus for heat treating air pervious material.

The term "air" is used herein broadly to include any attempering gas.

The apparatus disclosed herein is adapted to pass all or a controlled amount of the attempering air employed directly through a strip of material which it is desired to heat treat or otherwise attemper, as for example for drying, curing, or baking, or for fixing a substance, such for example as resin, in or on the material, or for a combination of these purposes.

An object of the invention is to provide a simple, practical and efficient apparatus of the above mentioned kind.

Another object of the invention is to provide apparatus adapted for uniformly heat treating material.

Another object of the invention is to provide a device which when used for curing is adapted to raise all portions of material being cured, uniformly and in the same time interval, to the same temperature.

Another object of the invention is to provide apparatus which when used for drying is adapted to remove moisture from all portions of the material, uniformly and in the same time interval, and to remove moisture from the interior of the material being dried substantially simultaneously with, and to the same extent as, the exterior surfaces of the material.

Another object of the invention is to provide apparatus for accomplishing the above mentioned objects while regulating the speed of travel of the material in accordance with its character, condition, and the temperature employed to produce a uniform product unimpaired in quality.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claim.

The invention will best be understood if the following description is read in connection with the drawings, in which,

Figure 1 is a front elevation of an embodiment of the invention, taken on the line 1—1 of Figure 2; and

Figure 2 is a side elevation of the apparatus

2

illustrated in Figure 1, taken on the line 2—2 of Figure 1.

The apparatus shown herein comprises a closed chamber 10 the front wall of which is provided with a horizontal slot 11 and the rear wall of which is provided with the horizontal slot 12, preferably aligned to permit a strip of material M to be passed into, through, and out of the chamber, in a straight horizontal run.

Above the path of the strip of material M the air impeller 13 is provided adapted to direct air downwardly through the flared hood 14 and the laterally extending air vents or nozzles 15 which are positioned just above, and are directed toward, the path of the strip of material to be treated.

Below the path of the strip of cloth M there is provided a perforated backing member 16 which serves to support the strip of material M and prevent it from being deflected by the force of the air from the air vents 15. Extending across chamber 10 and downwardly from directly beneath the perforated backing member 16 is an exhaust passage 17, which may be provided with any suitable means such for example as exhaust fan 18, to aid in drawing out through the exhaust passage the air which has entered the top of the exhaust passage after passing through the strip of material M. The exhaust passage 17 extends transversely of chamber 10 and is preferably located adjacent the front wall of the chamber so that the portion of the attempering air which has passed through the wettest portion of the incoming strip of cloth will be exhausted. As illustrated the exhaust passage 17 extends transversely across the chamber beneath the perforated backing member 16 from the front wall of the chamber approximately one-sixth of the depth of the chamber and thus exhausts approximately one-sixth of the air passing through the strip of material being treated. The area of exhaust passage 17 may be varied in accordance with the character and condition of the material being treated to provide a suitable and efficient ratio between the amount of air or other drying gas being exhausted and replaced and the amount being recirculated.

Positioned within the chamber 10 directly below the perforated backing member 16, and extending across chamber 10 within the mouth of exhaust passage 17 in the embodiment of the invention shown herein, is the conduit 18^a in which a partial vacuum may be drawn when desired, as for a drying operation, by any suitable means, not shown. The conduit 18^a extends transversely of

chamber 10 and at its top has a slot 19 preferably directly aligned with one of the slots or perforations of backing member 16 so that a suction action is exerted on the material through slot 19 tending first to draw off any loose moisture entrained on the strip. The effectiveness of this vacuum slot is greatly increased by its utilization within chamber 10 where it coacts with the air impeller or fan 13 in causing highly heated air to pass through the strip of material M. This co-operative action results in increasing the speed and therefore the volume of air passing through the strip within a given interval. This speed is further increased due to the fact that the hot air cools rapidly while passing through a moist strip M with the result that it rapidly loses volume and contracts. Since the vacuum pump operating in conduit 18 will have a substantially constant R. P. M. the result of this decrease in volume is that more air is pulled through the strip into conduit 18 within a given interval of time. The accelerated drying thus obtained may be increased by employing a plurality of conduits 18.

Thus in the event the apparatus is being used to dry wet material the utilization of the vacuum slot within chamber 10 serves to speedily reduce the moisture content of the material M, and consequently reduces the length of travel of the material, the time of treatment, or both, required for completing the drying of the material within chamber 10.

If chamber 10 is being used for curing material which has already been dried the extent of vacuum drawn upon conduit 18 may be varied as desired, or it may be cut out entirely if for any reason a curing or baking operation is desired and moisture removal is not desired.

Extending through chamber 10 from rear to front, on either side of the path of the material M and below it are the heater units 20, which are illustrated as gas heaters but may be any suitable source of heat, the heating means utilized being preferably capable of heating the air which is brought into contact with the travelling strip of material M to a temperature well above 200° F. and desirably to from 300° F. to 800° F. or even higher.

The air impeller means 13 may be driven by any suitable means, as for example by drive pulley 13a. As illustrated herein a double inlet fan is employed which sucks air in from both sides and forces air down through the flared hood 14 and through the laterally extending slots or nozzles 15 which, as has been stated, are directed toward the portion of a strip of material extending through chamber 10 between the front and rear wall slots 11 and 12 respectively. The air which passes through the strip M and is not exhausted through exhaust passage 17, or vacuum conduit 18, flows into close proximity to the heating units 20 and, after being reheated thereby, is returned and drawn into the opposite open ends of air impeller means 13 and recirculated. Any air which is deflected from the strip may be similarly recirculated.

A damper 22 is provided to substantially close the slot 11 in the front wall of chamber 10 without interfering with the entry of material M, and it will be seen that the pressure of air passing downwardly in the space between the ends of the air vents 15 and the cloth will tend to maintain damper 22 in closed position.

Air is ordinarily permitted to enter into chamber 10 through slot 12 and is ordinarily deflected into the upper portion of chamber 10 by the

damper 23 which is positioned intermediate a damper 24, by which the amount of outside air entering chamber 10 may be regulated, and damper 25, which controls whether all of the air from air vents 15 is forced through the strip of material M or whether a portion thereof is deflected from the surface of the material M and recirculated.

In the position of damper 25 as shown in full lines in Figure 2, with dampers 22 and 23 both closed, it will be noted that a pressure chamber is provided, the top of which is defined by the bottom of flared hood 14 which terminates in the transversely extending air vents or nozzles 15, and of which the side walls are provided by the dampers 22, and 23 and 25 respectively, and the bottom of which is defined by that portion of the strip of material M which happens to be within chamber 10. The pressure within this chamber is readily controlled by the damper means provided, primarily by damper 25, and when the damper means are closed the pressure built up within the said pressure chamber will force all of the air supplied from air impeller 13 to pass directly through the strip of material M, and thus all of the air will be caused to come in contact with the interior of the strip M as well as with its upper and lower surface portions. As a result very even drying or curing may be obtained.

In the case of material which is mainly surface impregnated, as in heavier fabrics such as plush and the like, the damper means may be readily regulated as by moving damper 25 from its closed position, indicated in full lines, toward its open position, indicated in broken lines, so that only part of the air supplied from air impeller 13 will be forced through material M and a part, regulated according to the need, will be deflected from the upper surface of the cloth.

The device described herein is not only exceedingly flexible but has much less bulk than similar apparatus now in use for drying, curing, or baking strip material such, for example, as textile fabric, paper, and the like. Because of its even, uniform treatment very high speeds of travel of the material and very high temperatures of the attempering air, are made possible.

It will thus be seen that there has been provided by this invention an apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

What we claim is:

Apparatus for conditioning and drying a strip of textile material which comprises a closed chamber having exit and entrance openings for the strip of material, means for supporting said strip of material for travel through said chamber, a port for admitting air into said chamber, an air exhaust port, means for controlling the volume of air admitted into and exhausted from said chamber, air heating means positioned in said chamber adjacent the air inlet, and means for directing the heated air against the surface of the material, a perforated support member extending across the chamber on the side of the

material remote from said air directing means, the walls of said air directing means forming, together with the chamber walls, air passages leading from beyond said perforated member and from the surface of the strip of material against which the air is directed back to said heating means, whereby air which is passed through the dryer portion of the material and air which has been deflected from the surface of the material is returned, mixed with incoming air, and re-heated and recirculated, and individual means for controlling the flow through said passages.
